(57) CLAIM

An ornamental design for footwear, as shown and described.

DESCRIPTION

FIG. 1 is a front perspective view of a shoe showing my footwear design;

FIG. 2 is a left side view of the footwear shown in FIG. 1; FIG. 3 is a right side view of the footwear shown in FIG. 1; FIG. 4 is a front view of the footwear shown in FIG. 1; FIG. 5 is a rear view of the footwear shown in FIG. 1; and, FIG. 6 is a top view of the footwear shown in FIG. 1.

The phantom lines showing portions of a shoe in FIGS. 1–6 are for illustrative purposes only and form no part of the claimed design. The bottom of the shoe is devoid of surface ornamentation and a view thereof is omitted.

1 Claim, 6 Drawing Sheets

FIG. 1

FIG. 2

FIG. 3

FIG. 4

FIG. 5
